UNITED STATES PATENT OFFICE.

DANIEL OTTO, OF DANVERS, ILLINOIS.

COMBINED GRAIN ELEVATOR AND DUMP.

No. 802,309.

Specification of Letters Patent.

Patented Oct. 17, 1905.

Application filed October 15, 1904. Serial No. 228,600.

To all whom it may concern:

Be it known that I, DANIEL OTTO, a citizen of the United States, residing at Danvers, in the county of McLean and State of Illinois, have invented new and useful Improvements 5 in a Combined Grain Elevator and Dump, of which the following is a specification.

My invention relates to improvements in what may be termed "combined grain loading 10 or elevating and dumping devices." It has for its object to provide for the convenient or mechanical tilting of the loaded wagon, as in dumping its load or contents, and to readily elevate or transfer such contents to a car or 15 bin in an expeditious and effective manner.

Said invention consists of certain structural features, substantially as hereinafter more fully disclosed, and particularly pointed out by the claims.

In the accompanying drawings, illustrating the preferred embodiment of my invention, Figure 1 is a plan view thereof. Fig. 2 is a vertical longitudinal section therethrough. Fig. 3 is an enlarged detailed view in side elevation, showing more especially the motor or tumbling-rod-actuated shaft, the wagon-platform-tilting gear, and shaft-actuating mechanism, including the clutch-shipping lever for reversing the direction of turning of the clutch-carrying shaft and the endless belt carrying the lug for actuating said clutch-shipping lever. Fig. 4 is an inverse view of the clutch-shipping lever disassociated from the other parts recited in Fig. 3. Fig. 5 is a transverse section produced through Fig. 3 intermediately of the intergeared connection and the gear and belt connection between the tumbler-rod-actuated shaft and the counter-shaft used in connection therewith. Fig. 6 is a corresponding section taken through the wagon tilting or dumping platform and main platform or bridge adjacent to the actuating-shaft and the chains or cables connected to said shaft for said tilting platform. Fig. 7 is a like section produced on a line passing through the main platform adjacently to the "chock" or stop for the hind wheels of the vehicle or wagon, as when in tilted position thereon. Fig. 8 is a broken vertical longitudinal section taken through the elevator, including two sections or members. Fig. 9 is a cross-section thereof produced near the derrick, or rather the swinging upright frame thereof and the elevator-suspending 55 stirrup or yoke, as viewed from the receiving side thereof. Fig. 10 is an enlarged de-

tached view showing more particularly the chock or stop and its spring connection with the wagon or vehicle platform tilting lever mechanism. Fig. 11 is a view showing the 60 clutch or coupling member receiving plate applied to the shipping-lever with its sections disassembled. Fig. 12 is a broken-away detailed view showing more particularly the lugs of the combined guards and stops secured 65 to the grain-receiving trough-like receptacle for limiting the downward and outward movement of the hinged member of said receptacle.

In the carrying out of my invention I suitably construct a main platform or support 1, preferably of longitudinal edgewise-arranged timbers 1^a with slanting ends and of transverse boards 1^b nailed or otherwise secured down upon said timbers throughout, thus providing for the ready driving on and off the same 75 of a loaded team or wagon, and which platform has preferably secured thereto in any suitable way a draft-bar 1^c for the convenient removal thereof from place to place as it may be needed for use. Suitably braced upright 80 frames or standards 2 are secured laterally to the platform 1 at opposite points, near one end thereof, with the vertical member or timber of each such upright frame having its diagonal or inclined member or brace 2^a secured 85 near its upper end upon the correspondingly-chamfered end of said vertical member or timber and extending beyond and suitably overhanging the latter for a purpose presently made apparent. 90

Suitably secured to the lower side of opposite lateral bars or timbers 3 are preferably two spaced-apart transverse bars or beams 3^a, principally constituting what may be termed the "wagon tilting or dumping platform," 95 such spacing apart of said bars being adapted to aid, as readily appreciated, the "chocking" of the wheels of the vehicle or wagon at its elevated end, as presently more fully made apparent. The lateral bars 3 of said platform are so disposed from their pivoting or bearing ends, as next described, as to enable the transverse or cross bars 3^a when said wagon-tilting platform is in its initial or horizontal position to rest upon the upper edges 100 of the timbers 1^a between certain of the boards 1^b, suitably spaced apart for that purpose, and thus constitute a part of the upper surface of the main platform for the loaded vehicle or wagon to travel upon as the latter is 105 brought into position for dumping or tilting. Said lateral bars 3 have their pivoting or bear- 110

ing ends preferably longitudinally slotted, as at 3^b, the slots thereof receiving lateral pivots 3^c, projecting from opposite uprights or studs 3^d, secured laterally to the platform or support 1, which pivoting or bearing ends or points are rendered adjustable, preferably by means of pins or keys 3^e, inserted through any two coincident apertures of two registering series thereof, 3^f, produced in each of said bars upon opposite sides of its slot. The insertion of said pins or keys through openings or apertures nearer to or farther from either end of each slot of each bar of course permits said bars to be suitably moved to effect the positioning of the tilting platform according to the length of the wagon or vehicle.

Pairs of opposite linked-together levers 4 are arranged in connection with the lateral bars of the tilting platform, the pivotal connection therebetween being effected about centrally of their connecting-links, and to the rear end of said levers, as also to said lateral bars, near the corresponding ends is suitably connected a chock or bar for obstructing or preventing the involuntary movement of the wagon or vehicle rear wheels when the wagon is in its tilted or dumping position. The connection between said chock and the levers 4 is effected by preferably right-angled hangers or brackets 5^a, fixed to said chock at its upper rear edges and pivoted to said levers, while a bail-like or bent rod 5^b has pivotal connection with the upper forward edge of said chock, the upturned or right-angled end portions of said rod being fixed to said lateral bars upon their lower surfaces to provide for the holding of said chock at its forward edge flush with the upper surface of the main platform 1 and to permit said chock to be inclined upward and rearward by said levers as said lateral bars comprised within the tilting platform are actuated or raised at their forward ends, together with the like movement of said tilting platform. A preferably coiled or helical spring 6 is interposed between the levers 4 and the bail-like connection 5^b to provide for automatically depressing or returning the chock 5^b to its initial or horizontal position when the tilting platform is returned or lowered to the corresponding position to effect the unchocking of the vehicle rear wheels at that time.

55 A shaft 7 is arranged down between upper surface-boards of the platform and journaled in any suitable way near the base of each upright frame or standard 2, upon one end of which shaft is secured a gear wheel or pinion 7^a, again later noted. To said shaft are connected and upon it are designed to be wound two chains or cables 8, engaging pulleys 9, hung in the overhanging upper end portions of the frames or standards 2, said cables or 60 chains then being engaged with pulleys 10,

hung upon and movable with the levers 4 in addition to having their hangers 10^a, which are pivoted upon said levers, also pivotally connected to the lateral bars 3 of the tilting platform. Said chains or cables are looped 70 back after having been engaged with pulleys 10 and fastened to the upper ends of the upright frames or standards 2, as shown, thus providing for suspending in position the tilting or dumping platform after having been 75 elevated. Said chains or cables of course serve by the aid of their winding and unwinding shaft 7 to primarily effect the raising and lowering of the tilting or dumping platform, as presently more fully disclosed. 8c

A shaft 11 is suitably journaled in position in one of the upright frames or standards 2 and an upright or standard 2^b, adjunctive thereof, as is also a counter-shaft 12, which shafts are adapted for conjoint and simultaneous action, as they are driven alternately in the same and reverse directions to accordingly affect the chain winding and unwinding shaft 7. To these ends the shafts 11 and 12 are provided with an intergeared relatively 90 large loose pinion or toothed wheel 11^a and a small pinion 12^a, respectively, also sprocket-pinions 11^b 12^b, respectively, the upper being loose, belted together by a link belt 13, the counter-shaft 12 having worm or screw 12^c 95 meshing or geared with the gear-wheel 7^a of the chain-actuating shaft 7. A suitable tightener or contrivance 14 for the effective action or engagement of the belt 13 with the sprocket-pinions 11^b 12^b is applied to a vertical piece 100 of one of the upright frames or standards 2. Said contrivance or tightener consists, preferably, of a right-angled member or casting 14^a, with one arm thereof adapted to be presented to and inflex said belt intermediately 105 of the sprocket-pinions 11^b 12^b to put the requisite stress upon said belt for an obvious purpose. The other arm of said bracket has a vertical slot 14^b extending therethrough and receiving a plate or bar 14^c, fixed laterally to 110 a member of the upright frame at that side, and working in said arm is a set or binding screw 14^d, adapted to be engaged with said plate or bar to provide for the adjustment of the tightener and holding it against the belt 115 13, as in properly stressing the latter.

The shaft 11, which is designed to be suitably connected to means for driving it, is provided with a sliding coupling clutch member 12^d, having the usual key or spline and slot 120 connection with said shaft and adapted to be alternately shipped into engagement with facing half-clutch members 12^e 12^{ee}, formed with the gear-wheel 11^a and sprocket-pinion 11^b, respectively, carried by said shaft and partaking of its movement and suitably delivering said movement, as above noted. An endless link belt 11^{aa} encompasses two sprocket-pinions 11^{bb}, one secured upon the shaft 7 at 125 one end and the other pinion suitably jour- 130

naled upon the platform 1 at its forward end, said belt being provided or equipped with a lateral lug 12^{cc} at a predetermined point thereon, the purpose of which will presently appear.

A shipping-lever 12^{dd} is suitably pivoted or fulcrumed in position to enable it to be engaged upon one side of its pivot at the required interval in the operation of the aforementioned parts, as presently explained, by the lateral lug 12^{cc} of the belt 11^{aa}. Said lever is adapted to effect connection upon the other side of its pivot with and actuate the clutch or coupling member 12^d, let into a correspondingly-slotted preferably bisected plate 12^{df}, with the meeting ends of its sections produced each with a half of the clutch-receiving slot thus formed, said plate or plate-sections being suitably secured to said lever, preferably as shown.

Adapted to be suitably disposed or adjusted with relation to the platform 1 is means for receiving and elevating the grain or contents of the loaded vehicle or wagon driven upon said platform, the same comprising an elevator 16, pivotally supported at its lower end within the bottom or base-frame 17^a of a kind of truck or skid 17, and of a supplemental elevator 16^a, pivoted or connected to and adapted to deliver into the elevator proper, 16. The supplemental member 16^a comprises a preferably rectangular trough-like receptacle adapted, as indicated, to be positioned upon the platform 1 near the rear end of the latter, and has its endless belt of carrying devices or carriers 16^b suitably arranged therein for the effective conduct and delivery of its contents to the corresponding endless belt of carrying devices or carrier 16^x of the elevator proper. Said endless belts of carriers or elevators 16^b 16^x are interacting or connected for continuous and simultaneous operation for obvious reasons. The power for effecting the operation of said endless belts of carriers of said elevators may be suitably applied thereto, as at 16^{ab}, and the connection therebetween and the motor or horse-power may be accomplished in well-known way, as by gearing, pulleys and belts, or otherwise. Said trough-like receptacle has upon its receiving side at the upper edge a pivoted or hinged section or member 16^c, adapted to be so disposed by suitably pressing or acting thereon with the hand or otherwise as to assume an upward and outward inclination, it being restricted in its movement, as presently seen. Combined stops and guards 16^d consist, preferably, of metal plates suitably improvised or bent to permit their being secured, preferably, to the inner surface of the trough-like receptacle laterally of the opening occupied by the member or section 16^c when moved into reverse position to that above ascribed to it, said plates extending edgewise through said opening and beyond said trough,

their lower edges at those points terminating in inward-extending lugs or stops proper, 16^{dd}, for restricting the downward and outward movement of said hinged section or member 16^c. It will be observed that, as noted, said plates serve to guard against the lateral escape of the grain or contents of the vehicle as the same is being dumped or passes therefrom and whatever may fall upon said member or section. The elevator proper, 16, is suitably suspended and adapted to be moved vertically within a pivoted frame or yoke 17^b of the truck 17 when in effective position, said elevator having pivotally connected thereto a bail 17^c, to which is connected a line or cable 17^d, passing over a pulley 17^e, hung from the upper end of said frame. Said line or cable is next passed and connected to and suitably wound upon the drum or cylinder of a windlass 17^f, whose shaft is journaled laterally upon the part 16. By suitably actuating said windlass the elevator of course may be raised and lowered as desired, as when arranged for use or when it may be desired to fold or collapse the same for convenience in moving the machine from place to place. As the frame or yoke 17^b, as before stated, is pivoted, it may be simultaneously collapsed or folded with the elevator, while the pivoted trough-like receptacle or member 16^c may be folded to back upon said elevator and these several parts bodily be piled or placed upon the main platform, with the tilting platform lowered thereinto, thus providing for the very compact folding and disposing of the same, as desirable in their transportation.

It will be noted that the loaded vehicle having been driven from the left upon the platform 1 and the team of course thereafter unhitched and removed the requisite movement is transmitted to the shaft 11 from the source of driving-power, putting in operation the gear and shaft actuating mechanism before described, the shipper or lever, however, rendering at this time effective the belted-together sprocket-pinions 11^b 12^b, consequently raising or inclining the tilting platform upon which the forward wheels of said vehicle are standing, accordingly disposing or inclining the vehicle. This will, it is obvious, result in so inclining or tilting the vehicle or wagon tailgate endward that upon suitably adjusting said tail-gate the grain or contents of the vehicle will gradually flow therefrom and enter or be dumped into the trough-like receptacle discharging into the elevator proper, above noted, thus providing for the delivery of said grain or contents of the vehicle into a car, bin, or other elevated point. As during the action of the aforesaid gear, &c., actuating mechanism the belt 12^{aa}, carrying the lateral lug 12^{cc}, is of course in motion, said lug will, by about the time the tilting platform reaches its maximum inclination, effect engagement with the clutch-shipping lever from the right

- and unship the clutch from the sprocket-wheel 11^b at that side, and thus provide for stopping said action of parts when the unloading operation will have been effected. At this juncture the transit of the clutch or coupling member upon the shaft 11, under the action of said shipping-lever, across to and its engagement with the sprocket-pinion 11^a will again set in action the aforesaid gear-actuating mechanism, this time in an opposite or reverse direction, consequently providing for the lowering of said tilting platform with its superincumbent weight—that of the unloaded vehicle. As during this reversed action of parts the belt 12^a with its lug 12^c will accordingly travel in the opposite or reverse direction, and about the time the tilting platform has reached its lower point said lug will have been oppositely brought into engagement with said shipping-lever, the clutch or coupling member will then be disengaged from said pinion 11^a, and thus stop the action of said gear-actuating mechanism for the repetition of the aforesaid operation.
- It will be noted that the tilting platform bearing the vehicle is more slowly raised through the belt and sprocket gearing than it is lowered through the spur-gearing, as above disclosed, for obvious reasons.
- Latitude is allowed as to details herein, as they may be changed as circumstances suggest without departing from the spirit of my invention.
- I claim—
1. A machine of the character described, employing a base-platform, a tilting or dumping platform mounted upon the latter, means for actuating said tilting platform, chocking means actuated conjointly with the actuating of said tilting platform and an elevator relatively arranged to said tilting or dumping platform.
  2. A machine of the character described, employing a base or platform, a vehicle tilting or dumping platform arranged in connection with the latter, means for actuating said tilting platform, and wheel-chocking means actuated conjointly with the actuating of said tilting platform.
  3. A machine of the character described, employing a base-platform, a tilting or dumping platform arranged thereupon and provided with linked-together levers, a chocking-bar arranged transversely upon said base-platform and connected to said levers, and means for the vertical adjustment of said tilting platform from one end.
  4. A machine of the character described, employing a tilting platform, intergeared shafts, said shafts also having belt and sprocket pinion connection, a clutch-shipper arranged for coaction with a sliding clutch member upon one of said shafts, said clutch member adapted for coöperation with the gear and sprocket wheels of said shaft, a chain

or cable actuating shaft, with the chains or cables thereof adapted to actuate said platform, an endless belt driven from said cable-winding shaft and equipped with a lug for engagement with said clutch-shipper, means for actuating said cable-winding shaft from one of the above said intergeared shafts, and means for actuating said clutch-member-carrying shaft.

5. A machine of the character described, employing a tilting platform, intergeared shafts, said shafts also having belt and sprocket pinion connection and carrying a sliding clutch member, a clutch-shipper adapted to actuate said clutch member, and render it effective for either said gear connection or for said sprocket-pinion connection, a chain or cable actuating shaft, with the chains or cables thereof adapted to actuate said platform, said cable or chain actuating shaft also having a gear-wheel, and one of said intergeared shafts having a worm or screw intermeshing with the latter gear-wheel, an endless belt driven from said chain or cable actuating shaft and equipped with a lateral lug adapted to engage said clutch-shipper, and means for actuating the other of said intergeared shafts.

6. A machine of the character described, employing a base-platform, a tilting platform having lateral endwise-adjustable bars and arranged in connection with said base-platform, and means for actuating said tilting platform.

7. A machine of the character described, employing a base-platform, a tilting platform having lateral bars each provided with a slot in one end adapted to receive a lateral pivot at each side of said base-platform, and adjusting pins inserted into said lateral bars; transversely through the slots therein, and means for actuating said tilting platform.

8. A machine of the character described, employing a base-platform, a tilting platform having pivoted thereto linked-together levers, a chocking-bar hung from the rear ends of the lateral bars of said tilting platform, said levers having connection with said chocking-bar for its actuation or adjustment, and means for the actuation of said levers and of said tilting platform.

9. A machine of the character described, employing a base-platform, a tilting platform superposed thereon and having pivoted thereto linked-together levers, a chocking-bar hung from the lateral bars of said tilting platform, a spring connected to said levers and indirectly to said base-platform for the automatic actuation of said chocking-bar, said levers having connection with said chocking-bar, a cable or chain actuating shaft, with the chains or cables thereof encompassing pulleys hung upon said levers, and means for actuating said shaft.

10. A machine of the character described,

employing a base-platform, a tilting platform superposed thereon and having pivoted thereto linked-together levers, a chocking-bar hung from the lateral bars of said tilting platform, said levers being connected to said chocking-bar, a cable or chain actuating shaft, with its chains or cables encompassing pulleys hung upon said levers, the hangers of said pulleys being connected to the tilting

platform lateral bars for conjoint movement to with said platform and levers, and means for actuating said shaft.

In testimony whereof I affix my signature in presence of two subscribing witnesses.

DANIEL OTTO.
